US00D895630S

(12) **United States Design Patent** (10) Patent No.: **US D895,630 S**
(45) Date of Patent: **** Sep. 8, 2020**

- (54) **CASE FOR TABLET-SHAPED PORTABLE ELECTRONIC COMPUTING DEVICE**
- (71) Applicant: **Pioneer Square Brands, Inc.**, Seattle, WA (US)
- (72) Inventors: **Brian Lewis Piper**, Seattle, WA (US); **Michael Cooper Ferren**, Camus, WA (US)
- (73) Assignee: **PIONEER SQUARE BRANDS, INC.**, McLean, VA (US)
- (**) Term: **15 Years**
- (21) Appl. No.: **29/735,367**
- (22) Filed: **May 20, 2020**
- (51) LOC (12) Cl. **14-02**
- (52) U.S. Cl. **USPC D14/440**
- (58) **Field of Classification Search**

(57) **CLAIM**

The ornamental design for a case for tablet-shaped portable electronic computing device, as shown and described.

DESCRIPTION

FIG. 1 is a top perspective view of a case for tablet-shaped portable electronic computing device showing our new design;

FIG. 2 is a top plan view thereof;

FIG. 3 is a bottom plan view thereof;

FIG. 4 is a front elevation view thereof;

FIG. 5 is a rear elevational view thereof;

FIG. 6 is a right elevational view thereof; and,

FIG. 7 is a left elevational view thereof.

The features shown in broken lines in the drawing figures depict features that form no part of the claimed design.

1 Claim, 4 Drawing Sheets
